LAMP DIMMING SYSTEM

George Alvin Brettell, Jr., Newark, N. J., assignor
to American Transformer Company, Newark,
N. J.

Application August 24, 1939, Serial No. 291,685

6 Claims. (Cl. 175—312)

This invention relates to the transmission of lighting current to electric lamps, and more particularly to the control of the lighting current for the purpose of dimming the lamps. The invention is applicable to the dimming of lamps used for a variety of purposes, and a particular example is the dimming of theater lamps.

To dim theater lamps or the like by means of series rheostats, requires bulky and expensive equipment, involves large power loss, and provides only make-shift control. Variations in the size of the lamp load correspondingly affect the degree of dimming produced by a given rheostat setting. To dim with reactors or variable transformers involves similar difficulties, in more or less degree, and makes it particularly burdensome to provide progressive dimming from full lamp intensity to complete extinguishment.

It has been proposed to dim theater lights by means of relay arrangements. These can avoid some of the objections inherent in rheostat, reactor, and transformer dimming. However, relay arrangements have not achieved a desirable degree of mechanical and electrical simplicity; nor have they reduced the cost of equipment and the amount of power loss to the extent that is desirable.

Among the general objects of the present invention are to simplify and reduce the cost of dimming equipment; to provide for low power loss; and to provide for flexible and positive dimming control.

Another object is to achieve the foregoing results with equipment which can be substituted in remote control systems that are now in common use.

A further object is to provide dimming apparatus which delivers controlled voltage to the lamp load, which voltage is substantially independent of variations in the size of the lamp load within the rated capacity of the dimming apparatus.

A still further object is to provide dimming apparatus which completely eliminates the flow of current in the lamp circuit when pilot control power is zero or at a minimum.

Various other objects and advantages will be apparent to those skilled in the art from the following disclosure.

Fig. 1 of the drawings shows voltage curves illustrating electrical principles utilized in the present invention.

Figs. 2 and 3 are voltage curves illustrating electrical changes involved in the dimming operation.

Fig. 4 is a schematic diagram showing dimming apparatus embodying the present invention.

Fig. 5 is a wiring diagram illustrating one method of paralleling the discharge tubes.

Reference will first be had to Figs. 1, 2 and 3. Wave 10 is a sine wave corresponding to the voltage delivered by the conventional alternating current power supply. The lamp load is connected to such a power supply, but in series with the load there is connected a pair of electric discharge tubes each having an anode, a cathode, and control means. Each tube is normally non-conducting, i. e., it blocks the flow of current until the control means becomes effective to "fire" the tube, i. e., render it conducting. Once a tube is fired it remains conducting during the remainder of the power half cycle, i. e. until the current wave passes through zero. Thus, if a tube is fired at time t_1 (Fig. 1) current will flow to the lamp load during the interval t_1 to t_2 and then be blocked out again. The tubes are asymmetric conductors, and hence can conduct current in one direction only. However, by using a pair of tubes, one tube can be connected to fire and then transmit lighting current during an end fragment of each positive power pulse, and the other tube can be connected to fire and then transmit lighting current during an end fragment of each negative power pulse. The net result of such action is to energize the lamp load with a non-sinusoidal alternating current corresponding to the non-sinusoidal alternating voltage represented by curve 11. Voltage curve 11 is spaced from voltage curve 10 by an amount equal to the voltage drop across the tube when the tube is conducting. By shifting the time of firing with respect to wave 10, different sized fragments of the half cycles in wave 10 are applied to the lamp load, thereby varying the effective energization of the lamps.

The electric discharge tubes that produce wave 11 may be of various types which permit of adequate control of the discharge stream to thereby control the time of firing. Among such types of tubes are hot cathode gaseous or vapor tubes with grid or magnetic control, and mercury pool tubes with ignition control. Of the tubes which are commercially available at present, I prefer Xenon-filled, hot cathode, grid controlled tubes. When I refer to using a pair of tubes, or two tubes, I also include a case where a single envelope may be used to inclose the structure functioning as two tubes, as well as including a case where additional tubes may be paralleled or otherwise combined with the first two for the pur-

pose of increasing the load-carrying capabilities of the apparatus.

With a grid controlled tube the firing of the tube is determined by the grid potential. Figs. 2 and 3 assume a tube which fires when the grid potential is raised to a value equal to the axis potential of the applied power wave 10. A control voltage wave 12 lags power wave 10, e. g. by about 110 degrees. The potential of wave 12 is applied to the grid; and when the axis of wave 12 rises to the axis of wave 10, as shown in Fig. 2, the tube fires and conducts during the remainder of the half cycle of wave 10. Thus the shaded portion of wave 10 of Fig. 2 represents the fragment of the positive power pulse which is rendered effective to send current to the lamp load. Fig. 3 illustrates the effect of depressing control wave 12, e. g., by also impressing upon the grid a negative D. C. bias v . The effective fragment of wave 10 is diminished as indicated by the shaded portion in Fig. 3.

The system is so set up that full lamp brilliancy is obtained without utilizing all of power wave 10. By shifting the control wave 12, progressively smaller fragments of wave 10 are applied to the lamp load, thereby progressively dimming the lamps. It will be apparent that continued depression of wave 12 will result in that wave not ascending to the axis until the point where wave 10 has descended to the axis. Then the shaded area (e. g. in Fig. 3) will vanish and no current will be delivered to the lamp load. Instead of elevating and depressing control wave 12 by means of D. C. bias, the phase of wave 12 (with respect to wave 10) can be shifted to accomplish the same result, or a peaked wave can be used where the time of the peak is changed.

Reference will now be had to Fig. 4. This figure contains various duplicated elements symmetrically arranged. In general only one set of elements will be described, but the same reference characters with a prime mark added thereto will be applied to the duplicate elements.

A lamp load 15 is connected to a conventional source of alternating current 16. In series with the lamp load is a pair of gaseous rectifier tubes 17 and 17', one to transmit fragments of the positive power pulses and the other to transmit fragments of the negative power pulses. Connected in bridge of source 16 is a transformer 18 having secondary windings 19 and 20. Winding 19 is connected to energize the cathode of tube 17; and winding 20 energizes a closed loop 21 from which a control voltage wave (such as wave 12 in Figs. 2 and 3) is derived to influence the grid of tube 17. The lag of the control voltage is produced by condenser 22 and resistance 24. An auxiliary rectifier 25, also energized from winding 20, furnishes a fixed D. C. negative bias for the grid of tube 17, this bias being sufficient to block the tube in spite of the effect of the control A. C. wave. Thus, in the absence of a definite pilot voltage to set the tube 17 in operation, such tube remains blocked and no current flows to load 15. The pilot voltage is furnished from full wave rectifier 26 and is adjustable to overpower the bias from auxiliary rectifier 25, and thus elevate and depress the A. C. control wave to thereby regulate the effective current transmitted to the lamp load as explained in connection with Figs. 2 and 3.

The circuit for auxiliary rectifier 25 is from the center tap of winding 20, rectifier 25, loading resistance 27 which is shunted by smoothing con-

denser 28, and back to the right-hand end of winding 20.

Full wave rectifier 26 is energized from a transformer 29 having a variable input connection at 30. As shown, the input of transformer 29 is connected for energization from the power source 16. The output terminals of full wave rectifier 26 are connected to the center taps of the isolating choke 31-32. Bridged across the output of rectifier 26 is a loading resistance 34 which is shunted by a smoothing condenser 35.

The grid circuit for tube 17 is from the grid thereof, isolating resistor 36, left half of winding 31, resistance 34, left half of winding 32, resistance 24, resistance 27, center tap of filament winding 19, and cathode of tube 17. Similarly, the grid circuit for tube 17' is from the grid thereof, isolating resistor 36', right half of winding 31, resistance 34, right half of winding 32, resistance 24', resistance 27', center tap of filament winding 19', and cathode of tube 17'. It will be noted that these grid circuits are not blocked by condensers, and therefore they can impress D. C. bias as well as A. C. potential on the grids.

When tube 17 is conducting (during a power pulse in one direction from source 16) lighting current flows from power source 16, conductor 37, lamp load 15, conductors 38 and 39, anode of tube 17, cathode of tube 17, filament winding 19, center tap of winding 19, and conductors 40, 41, and 42 back to source 16. When tube 17' is conducting (during a power pulse in the opposite direction from source 16) lighting current flows from power source 16, conductors 42, 41, and 39', anode of tube 17', cathode of tube 17', filament winding 19', center tap of winding 19', conductors 40' and 38, lamp load 15, and conductor 37 back to source 16.

Assume the adjustment at 30 to be in a position which gives zero input to transformer 29. The lagging A. C. control voltage-drops across resistances 24 and 24' are impressed upon the grids of tubes 17 and 17' respectively, since these resistances are in the respective grid circuits. However, these grid circuits also contain resistances 27 and 27', respectively, through which direct current flows from auxiliary rectifiers 25 and 25', respectively; and the D. C. voltage-drops across resistances 27 and 27' keep the tubes 17 and 17' blocked. Thus, no lighting current flows; and it will be noted that in this condition the pilot input to transformer 29 is also zero. As adjustment 30 is moved to increasingly energize transformer 29, a progressively increasing positive bias is added to the two grid circuits by the increasing voltage-drop across resistance 34. This positive bias overpowers the blocking biases from auxiliary rectifiers 25 and 25' and elevates the axes of the respective control voltage waves impressed on the grid circuits by resistances 24 and 24'. Thus, the lamp load is increasingly energized as will be clear from the explanation given in connection with Figs. 1, 2 and 3.

The ohmic resistance of a rheostat is independent of the current passing through it, so the voltage-drop which it imposes on a series circuit is equal to the rheostat resistance multiplied by the effective load current. Thus, the dimming effect of a series rheostat varies drastically with the load. With a gaseous conductor such as tubes 17 and 17', the ohmic resistance decreases as the load current increases; and the decrease is such that the voltage-drop imposed on the load circuit is substantially independent

of the load current. Thus, the system of the present invention gives uniform dimming regardless of the size of the lamp load, provided only that the load is within the rated capacity of the apparatus.

The lamp load 15 is, for present purposes, also a pure ohmic resistance load. Thus, the heating and therefore the illuminating effect of the lighting current is determined by the integrated root-mean-square value of the current regardless of the wave form of the current. However, because of the resistance characteristics of tubes 17 and 17', the heating effect of the load current on each tube is determined by the integrated average value of the current passing through the tube (which does not involve reversal of the wave). The integrated average value of the composite load current (which involves wave reversal) is zero. Thus, by using a wave form which has a root-mean-square value that is high in comparison to its average absolute value, the effective load carrying capabilities of tubes 17 and 17' are increased. This principle is utilized in the present invention.

The ratio of the integrated root-mean-square value to the integrated average value of a half cycle is commonly known as the form factor of the wave. For a pure sine wave the form factor is 1.1. In general electrical work high form factor is deleterious, and the attempt is made to keep it down as close to 1.1 as possible. However, high form factor with the present invention means less heating of tubes 17 and 17' for a given effective lighting current delivered to the lamp load. As a numerical example, a root-mean-square current of 25 amperes delivered to the lamp load at the sine wave form factor of 1.1 would mean that the two tubes together had to handle an average current of 22.8 amperes, whereas the same root-mean-square current delivered at a form factor of 2.0 would burden the two tubes together with an average current of only 12.5 amperes. Thus by so operating that wave 11 (Fig. 1) has a high form factor, the load carrying capabilities of tubes 17 and 17' are enhanced. In general, the nearer the point of fire occurs to the end of the half cycle of the wave, the higher the form factor of the load current. Thus, from this standpoint, it is desirable to utilize only a fragment of each power cycle even when the lamps are turned fully on. Under all dimmed conditions the load current will be less and the duty imposed on tubes 17 and 17' will be correspondingly less.

The load carrying capabilities of the apparatus may be augmented by adding a duplicate tube connected in parallel with tube 17, together with a second duplicate tube connected in parallel with tube 17'. Tube 17 and its duplicate will then fire simultaneously, a balance coil being used to divide the load equally between the two tubes. Similarly, tube 17' and its duplicate will fire simultaneously, each tube carrying half the load. Another way of utilizing the parallel arrangements of tubes is to arrange the grid circuits to fire tube 17 on one half cycle, and fire the paralleled duplicate tube on the next half cycle of the same sign. Similarly tube 17' and its duplicate may be alternately fired on half cycles of the opposite sign.

Fig. 5 illustrates a simple method by which the tubes may be paralleled to fire alternately. Here the plates P1 and P2 of the two tubes 47, 47', are directly connected together, as are also the cathodes C1 and C2. Now, if G1 is slightly

positive with respect to G2, a signal entering at 5 s will fire tube 47 in preference to tube 47'. Thus, if a source of 30-cycle voltage 43 be inserted at 44 and the plate and grid supplies be 60-cycle voltage, the tubes will alternate in carrying the load current. On the first cycle of the 60-cycle power supply tube 47 will fire while on the second cycle tube 47' will fire. The average load current will thus be split between the two tubes, enabling the combination to control twice the lamp capacity that one tube could. This particular system has the advantage of eliminating the bulky and expensive balance coil normally required.

15 In compliance with the patent statutes I have disclosed the best forms in which I have contemplated applying my invention. However, it will be understood that the disclosure is illustrative only; and it will be apparent to those skilled in the art that various substitutions, changes, and mutations may be made within the scope of the invention.

What is claimed is:

25 1. Apparatus for dimming electric lamps energized from a course of alternating current, said apparatus comprising a plurality of rectifying electric discharge devices connected to transmit the lighting current to the lamp load, said devices operating to deliver current having a form factor greater than 1.1 at maximum root-mean-square load current; and circuit connections protecting the load and source from any net direct current resulting from the rectifying action of 30 said discharge devices.

35 2. Apparatus for dimming electric lamps energized from a source of alternating current, said apparatus comprising electric discharge devices connected to control the lighting current delivered to the lamp load, said devices having means to initiate their conductivity, means to bias said conductivity-initiating means to normally block 40 said discharge devices and means to overpower said blocking biases and thereby fire said devices and cause lighting current of form factor 45 sensibly greater than 1.1 to be delivered to the lamp load.

3. Apparatus for dimming electric lamps energized from a source of alternating current, said apparatus comprising gaseous electric discharge devices connected to control the lighting current 50 delivered to the lamp load, said devices having electrodes the potential of which initiates the conductivity of the devices, means to bias said electrodes to normally block said discharge devices and control means operative to overpower 55 said blocking biases and thereby fire said devices and cause lighting current of form factor sensibly greater than 1.1 to be delivered to the lamp load, said control means being variable to regulate the effective value of said lighting current.

60 4. Apparatus for dimming electric lamps energized from a source of alternating current, said apparatus comprising a pair of rectifying gaseous electric discharge devices having electrodes 65 the potential of which initiates the conductivity of the devices, one of said devices being connected to deliver current to the lamp load during positive half cycles of the power source and the other being connected to deliver current to 70 the lamp load during negative half cycles of the power source; auxiliary rectifiers connected to bias said electrodes to normally block said discharge devices and a control rectifier and sources of control alternating current connected to overpower the bias imposed by each auxiliary recti-

fier and also render each discharge device conducting to transmit current of form factor sensibly greater than 1.1 to the lamp load.

5. Apparatus for dimming electric lamps energized from a source of alternating current, said apparatus comprising a pair of rectifying gaseous electric discharge devices having electrodes the potential of which initiates the conductivity of the devices, one of said devices being connected to deliver current to the lamp load during positive half cycles of the power source and the other being connected to deliver current to the lamp load during negative half cycles of the power source, auxiliary rectifiers connected to bias said electrodes to normally block said discharge devices, a control rectifier and sources of control alternating currents connected to overpower the bias imposed by each auxiliary recti-

fier and also render each discharge device conducting to transmit current to the lamp load and means to vary the time during the power cycle at which said discharge devices are rendered conducting such that at a maximum sensibly less than the complete cycle shall be used.

6. Light control means as herein disclosed, comprising electric discharge devices having parallel connected anodes and control electrodes, means for impressing an alternating current voltage on said parallel connected anodes and means for impressing an auxiliary signal between the two connected control electrodes of a frequency one half that of the anode voltage frequency to effect alternate firing of said discharge devices.

GEORGE ALVIN BRETELL, JR.
